US0D1035199S

(12) **United States Design Patent** (10) **Patent No.:** **US D1,035,199 S**
(45) **Date of Patent:** **** Jul. 9, 2024**

(54) **PAINT ROLLER CLEANING DEVICE**

(71) Applicant: **Port86, LLC**, Helena, MT (US)

(72) Inventors: **Patrick A. Williams**, Helena, MT (US);
Kimm L. Reid, Regina (CA)

(73) Assignee: **Port86, LLC**, Augusta, MT (US)

(**) Term: **15 Years**

(21) Appl. No.: **29/795,085**

(22) Filed: **Jun. 16, 2021**

Related U.S. Application Data

(63) Continuation-in-part of application No. 29/763,823, filed on Dec. 24, 2020.

(51) **LOC (14) Cl.** **07-05**

(52) **U.S. Cl.** **USPC D32/35**

(58) **Field of Classification Search**

USPC D32/1, 25, 35, 46; D8/14, 499; D9/455; D24/128

(57) **CLAIM**

The ornamental design for a paint roller cleaning device, as shown and described.

DESCRIPTION

FIG. 1 is a top perspective view of a new design for a paint roller cleaning device;

FIG. 2 is a bottom perspective view of FIG. 1;

FIG. 3 is a first side view of FIG. 1;

FIG. 4 is a second side view of FIG. 1;

FIG. 5 is a bottom view of FIG. 1;

FIG. 6 is a top view of FIG. 1;

FIG. 7 is a first end view of FIG. 1; and,

FIG. 8 is a second end view of FIG. 1.

The broken lines shown in FIGS. 2 and 5 depict portions of the article that form no part of the claimed design.

1 Claim, 8 Drawing Sheets
